UNITED STATES PATENT OFFICE.

TERENTIE DAVIDENIA, OF DETROIT, MICHIGAN.

RAILROAD-STATION INDICATOR.

1,386,606.

Specification of Letters Patent.

Patented Aug. 9, 1921.

Application filed July 14, 1920. Serial No. 396,151.

To all whom it may concern:

Be it known that I, TERENTIE DAVIDENIA, a citizen of Russia, residing at Detroit, county of Wayne, and State of Michigan, 5 have invented certain new and useful Improvements in Railroad-Station Indicators, of which the following is a specification.

This invention relates to improvements in station indicators, and it is the principal 10 object of the invention to provide a mechanically operated device of this kind by means of which each succeeding station *en route* is indicated in the individual cars of a train simultaneously.

15 A further object of the invention is to provide a device of this kind which can be conveniently attached to any type of cars at present in use and which is of an extremely simple and therefore inexpensive construction.

An exemplification of the invention is illustrated in the accompanying drawings forming a material part of this application, and in which—

25 Figure 1 shows in side view two coupled cars provided with the device constructed according to the present invention.

Fig. 2 is a side view in section of an end wall of a car equipped with the device, according to the present invention.

30 Fig. 3 is a front view of the indicator casing.

Fig. 4 is a top plan view of the casing in section.

35 Fig. 5 is a front view of the actuating mechanism of the device partly in section attached to the end wall of a car.

Spaced from the end wall 10 of each car 40 11 and 12, coupled together as at 13, within the vestibules 14 and 15 of these cars, a partition 16 is provided having in its lower part an opening 17 for the passage of a handle 18 adapted to be manually operated by one of the attendants as will be hereafter 45 more fully described.

In the upper part of the space formed by the car wall 10 and the partition wall 16, three shafts 19, 20 and 21 are journaled in these walls, each carrying a sprocket wheel 50 22, 23 and 24 respectively. A chain 25 is guided over the wheels 22 and 24, and the shafts of the wheels 22 and 24 are extended through the wall 10 of the car into a casing 27 and carry therein bevel gears 28.

55 The casing is secured to the inner car wall by brackets 29, and the bevel gears 28 are

in mesh with bevel gears 30 near the upper end of vertical shafts 31 journaled in the top and bottom walls of the casing 27. These shafts 31 carry each a drum 32 over 60 which a band 33 bearing a succession of station names is wound, so that when rotated in one direction, the band will be unwound from one of the drums and wound upon the other and vice versa, when rotated in the 65 opposite direction. The band at the front of the casing 27 is guided between guide plates 34 to pass a glass plate before an opening 35 of the front wall of the casing. Over the sprocket wheel 23 a chain 36 is 70 guided which is also guided at its lower end over a sprocket wheel 37 on a shaft 38 journaled in a bracket 39 secured to the bottom 40 of the car. The handle 18 passed through the opening 17 is secured to a sprocket wheel 75 41 secured on a shaft 42 journaled in the front wall 10 of the car and the partition wall 16. The shaft 38 is suspended longitudinally under the bottom of each car in suitable hangers 43 and at each of its ends, 80 at the end of each car, the shaft is flattened as at 44 and provided with holes 45 for the reception of coupling bolts 46 by means of which the shafts of two adjoining cars may be coupled, so that the operation of the indicator on one of the cars by the operation 85 of the handle 17 will operate also the indicators on all the other cars of a train.

From the foregoing description the operation of the device will be easily understood 90 without further explanation, and it will be clear that changes may be made in the arrangement of the parts and the construction of the minor details without deviating from the scope and spirit of the present invention. 95

Having thus described my invention, what I claim as new and desire to secure by Letters Patent of the United States is—

1. Mechanical operating means for the street or station indicators on each car of a 100 train of cars comprising a partition wall in spaced relation to the end wall of a car, and provided with an opening, horizontal shafts journaled in the end wall and the partition wall of the car, sprocket wheels on 105 two of said shafts, a chain guided over said sprocket wheels, a sprocket wheel on the third and central of said shafts, a sprocket wheel on a shaft journaled in a bracket at the car bottom, a chain guided over the last 110 named two sprocket wheels, means for operating said sprocket wheels and chains, and

means for coupling the shafts at the bottom of each car with the shaft at the bottom of the next succeeding car.

2. Mechanical means for operating the street or station indicators on each car of a train of cars simultaneously from one of the cars comprising a partition wall in spaced relation to the end wall of a car, provided with an opening near its lower end, a plurality of horizontal shafts journaled in the partition and the car wall near the upper ends thereof, sprocket wheels on the outer two shafts, a chain guided over said sprocket wheels, a sprocket wheel secured to a shaft journaled in a bracket on the car bottom, a chain guided over the last named

two sprocket wheels, a sprocket wheel on a shaft between said last named two sprocket wheels, a handle on said last named sprocket wheel passed through the opening in said partition wall, the shaft journaled in the brackets at the car bottom extended longitudinally across the bottom of each car and having flattened and perforated ends, and coupling pins passed through the openings of two adjoining shafts for operating the shafts and indicators on each of the cars of a train of cars from one of these cars.

In testimony whereof I have affixed my signature.

TERENTIE DAVIDENIA.
